(57) **CLAIM**

I claim the ornamental design for a circular laser saw, or similar article substantially as shown.

DESCRIPTION

FIG. 1 is a perspective view of the circular laser saw.

FIG. 2 is a right side view of the circular laser saw.

FIG. 3 is a left side view of the circular laser saw.

FIG. 4 is an elevational view of the circular laser saw.

FIG. 5 is an underneath view of the circular laser saw.

FIG. 6 is a front view of the circular laser saw; and,

FIG. 7 is a rear view of the circular laser saw.
